ABSTRACT OF THE DISCLOSURE

In a conventional mercury cell for producing chlorine and sodium hydroxide from brine, the mercury flows through the cell during electrolysis and picks up sodium to form an amalgam. The amalgam leaves the cell and is pumped or allowed to flow through a seal into a decomposer or "denuder" which is separate from the cell. In the present invention both the electrolysis of the brine and the decomposing of the amalgam are carried out in the same cell. The invention is based upon the utilization of a stationary film or layer of mercury and a non-amalgamable, electrically conductive, porous member such as graphite which is in direct contact with the bottom of the mercury layer.

BACKGROUND OF THE INVENTION

(1) Field of the invention

This invention relates to a method and apparatus for the electrolysis of an electrolyte solution of an alkali or suitable alkaline earth metal salt, typically a brine solution of sodium chloride. The invention more specifically relates to a special type of mercury cell for carrying out the foregoing electrolysis in order to produce anode electrolysis products, e.g. chlorine, and alkali or suitable alkaline earth metal reaction products, e.g. sodium hydroxide.

(2) Description of the prior art

In a conventional mercury cell for producing chlorine and sodium hydroxide, the mercury is polarized as a cathode in a strong brine solution against a graphite anode, a dimensionally stable anode or a porous flow-through graphite. The mercury flows through the cell during electrolysis and picks up alkali metal cations (most commonly sodium) to form an amalgam. The alkali metal content of the amalgam cannot be allowed to increase beyond a certain maximum concentration before the amalgam ceases to function efficiently and hydrogen and caustic alkali are liberated within the cell. In the conventional mercury cell, however, before this limiting concentration is reached the amalgam exits from the cell and is pumped or allowed to flow through a seal into a decomposer or "denuder" which is separate from the cell. The decomposer is usually a vessel packed with graphite, or graphite and iron, through which the amalgam can flow and where it can come into contact with purified water. An exothermic reaction occurs within the decomposer between the amalgam and the water to produce hydrogen and caustic alkali leaving behind an amalgam denuded of most of its alkali metal content. This denuded amalgam, i.e. mercury, is then pumped back to the electrolysis cell and the cycle of operations repeated.

In such a conventional mercury cell system substantial amounts of mercury are necessary to operate the cell. A mercury circulating pump and a separate decomposer or denuder is also necessary for each cell. It is also necessary to have the bottom of the cell tilted at a slight angle in order to obtain the desired mercury flow.

SUMMARY OF THE INVENTION

The invention described herein consists of basically the same brine flow, anode arrangement and mercury cathode system as is found in conventional cells. However, no re-circulating of the mercury (or alkali metal amalgam) is carried out but instead these are "stationary."

By "stationary" is meant that the mercury or the amalgam are not pumped or allowed to flow through a seal into a separate decomposing or denuding compartment as is common in a conventional mercury cell. Also, instead of the mercury being situated upon a steel, rubberized steel, or other solid bottom, the mercury rests on a porous plate or base. The porous plate has to be of a porosity which cannot be penetrated by the mercury or mercury amalgam under cell conditions but which can be permeated by purified water, steam or other alkali or alkaline earth metal oxidant. The porous material must also be essentially "non-amalgamable" with mercury, (i.e., a material which does not form an alloy with the mercury), stable to an alkaline and hydrogen environment, not have a high hydrogen overvoltage (whereby decomposition of amalgam would only occur slowly), and must also be a conductor of electricity so that it can act as a cathode in the decomposition reaction. Porous graphite, more fully described hereinafter, fulfills these requirements.

On the opposite side of the porous plate, below the mercury cathode, a compartment is fabricated, so that an alkali or alkaline earth metal oxidant, such as purified water or steam, can be led into the porous cell base. This is facilitated by applying a vacuum to the cell base. This vacuum must be sufficient to draw the alkali or alkaline earth metal oxidant through the pores to enable it to come into contact with the amalgam at the porous base/amalgam interface while not being a high enough vacuum to draw the mercury or amalgam cathode through the porous base. It has been found that reducing the absolute pressure to only 730 mm. of mercury is sufficient to draw over the oxidant, e.g. water or steam, without drawing the mercury or amalgam through the pores of a porous graphite cell base. A vacuum of 700 mm. of mercury is more preferred and this may typically be increased, without adverse results, to as low an absolute pressure as 500 mm. of mercury.

During operation of the cell the water in the pores at the porous base/amalgam interface reacts with the amalgam to form hydrogen and caustic alkali, which are drawn off from the base by the vacuum. The amalgam is therefore being continually denuded of its alkali or alkaline earth metal content and continues to operate efficiently without hydrogen evolution in the upper compartment situated over the mercury. In a system such as this there is a considerable reduction in the amount of mercury necessary to operate the cell. Less than 12 pounds of mercury is needed for every 1000 amperes capacity the cell has, rather than the 50 pounds or so that is presently required in a conventional mercury cell. With the mercury not being circulated the need for mercury circulating pumps and separate decomposers is eliminated. A single vacuum pump is typically sufficient to operate the denuding aspect of a whole cell room.

In accordance with the foregoing, therefore, it is an object of the present invention to considerably reduce the mercury inventory needed for the operation of a mercury cell.

Other objects are to:
Reduce the mercury loss associated with conventional denuding practice;
Eliminate the need for a mercury circulating pump on each cell;

Eliminate the need for a separate decomposer for each cell;

Eliminate the need to have the cell tilted at a slight angle in order to provide mercury flow;

Eliminate ripples in the mercury normally present in the flowing mercury, thereby allowing closer anode and cathode spacing, reducing operating costs; and to

Eliminate the need for weirs within the electrolyzer to prevent brine flowing out with the mercury.

Additional objects of the invention will become apparent from the detailed description of the invention which follows.

DESCRIPTION OF THE DRAWING

Details of the cell of the present invention are shown in FIGS. 1 and 2. FIG. 1 is a vertical sectional view of the cell. FIG. 2 is a horizontal sectional view taken across the plane 2—2 of FIG. 1. With reference to FIG. 1, the cell, indicated generally by the numeral 1, may be considered as comprising two distinct reaction compartments, upper compartment I and lower compartment II. The cell top 1a, bottom 1b, and sidewalls 1c, are all constructed of suitable non-electrically conductive, chemically inert material, or lined with a material 1d (such as rubber) possessing these properties.

The two compartments are separated by a stationary, substantially horizontal mercury cathode layer 2. Compartment I contains an electrolyte solution 3 of an alkali or suitable alkaline earth metal salt, such as a brine solution of sodium chloride to be electrolyzed; an electrolyte inlet means 4 and electrolyte outlet means 5. ("Suitable" alkaline earth metal salts refer to salts of calcium, barium and strontium.) Outlet means 5 may also be used to draw off anode electrolysis products (such as chlorine). Compartment I also contains at least one anode 6 (such as graphite), so positioned above the mercury cathode layer 2 as to form a suitable electrode gap between the anode and the mercury cathode layer. (FIG. 1 is illustrative only and should not be interpreted as drawn "to scale" with respect to this gap, or the thickness of the cathode layer 2, or the thickness of lining material 1d.) Compartment II, below the mercury, contains an electrically conductive, porous, non-amalgamable member 7, such as porous graphite, which is in direct contact with the bottom of the mercury layer 2, and which supports same. The compartment II also contains inlet means 8 and 8a for introducing an oxidant (such as steam) of the alkali or alkaline earth metal into and through the porous member 7, and outlet means 9 for removing reaction products resulting from the reaction between the metal oxidant (e.g. steam) and the alkali or alkaline earth metal amalgam produced in reaction compartment I.

The lower compartment has means for applying a slight vacuum to the underside of the porous, electrically conductive support member 7. Conduit 9 may be used both to remove reaction products and to apply vacuum. The potential between the anode and the cathode is applied by electrical connections 10a and 10b made to the anode and cathode, respectively. The electrical connection to the mercury cathode may typically be made through the electrically conductive, porous member which is beneath and in contact with the mercury cathode layer. The vacuum is applied by means of a vacuum pump (not shown) which applies a vacuum to the underside of the porous, electrically conductive support member through conduit 9 and vacuum pores 9a, thereby assisting in drawing the steam through the porous graphite and also in removing reaction products from the lower compartment of the cell. The porous support member is permeable to the steam (or alkali or alkaline earth metal oxidant) but is impermeable to the mercury under the cell operation conditions, which refer particularly to the temperatures used and the amount of vacuum employed.

A metal base 11, typically made from steel and shown in horizontal section in FIG. 2, is preferably employed

beneath the porous graphite member 7 in order to help support same and also to conveniently provide steam access holes 8a and vacuum pores 9a to facilitate introduction of the steam or metal oxidant and removal of the reaction products from the lower compartment. Typically the conductive porous member 7 and the metal base 11 will be made integral by cementing them at their adjoining faces thus helping to insure optimum and fixed location of holes 8a and 9a and also minimum voltage loss across this portion of the electrical circuit. (As indicated in FIG. 1, the electrical connection 10b to the mercury cathode is typically made directly to the metal base and then through the electrically conductive porous member 7). A good electrically conducting cement 12, resistant to the reactants and reaction products of the cell, such as a graphite filled epoxy cement, is therefore desirably employed to make an electrically conductive composite support for the mercury cathode.

DESCRIPTION OF THE PREFERRED EMBODIMENTS

An electrolytic cell was constructed having the features shown in the drawings. As previously pointed out the cell had two particularly unique features; first the mercury pool rested on a porous graphite base rather than the steel base common in commercial mercury cells; and second, the mercury or amalgam pool was stationary or confined in place rather than being pumped out of the cell recirculated through a decomposer and back to the electrolyzer as is common in conventional systems. Voltages between the decomposition potential of the alkali or alkaline earth metal salt being electrolyzed and about 6 volts, and current densities of up to 1 ampere per square centimeter (amp./sq./cm.) (or 10,000 amps per square meter, which is comparable with cathode current densities now used in industrial practice in electrolyzing NaCl brine) were applied to the cathode with successful denuding of the amalgam formed being obtained. It most of the tests conducted, sodium chloride brine solution was the salt electrolyzed; the anode used was fabricated from normal density graphite, the cell operated at temperatures between 70° C. and 90° C., and the electrolyte pH ranged from 1.9 to 2.5. Steam was used as the metal oxidant. (By "oxidant" is meant a material which is chemically reduced by the alkali or alkaline earth metal of the amalgam).

A vacuum of 700 mm. (Hg) was employed and this was sufficient to draw over the water (steam which condensed at the interface of the mercury layer and the porous graphite) without drawing the mercury through the pores of the porous graphite. During operation of the cell the water in the pores at the interface reacted with the sodium amalgam (as previously mentioned, the mercury changes to amalgam) to form hydrogen and caustic soda solution which were drawn off from the graphite by the vacuum. The slight vacuum prevented any hydrogen from going up through the thin mercury film. The amalgam was therefore being continually denuded of its alkali metal content and continued to operate efficiently in the electrolyzer (compartment I) without hydrogen evolution in that compartment. The current density coupled with the weight of mercury employed dictated a total mercury requirement of only 12 lbs. for every 1000 amps capacity the cell had and is to be compared to the 50 lbs. or more of mercury required for operation of a conventional mercury cell. As a result of this the present invention offers the capital advantage of massive reduction in the mercury inventory. The operating voltages of the cell were not affected by the stationary film principle. With in place regeneration of the mercury and the mercury not being circulated, the need for mercury circulating pumps and separate decomposers was eliminated.

It should also be noted that in the operation of mercury cells, metallic impurities such as V, Mo, Cr, Ti, Ta, (Mg

and Fe), Ni, Co, Fe and W, cause premature amalgam decomposition in the electrolysis compartment and have to be removed from the feed brine before it enters the cell. These impurities are excellent decomposition catalysts when added to the porous graphite of the present invention and greatly improved the denuding characteristics of the described system. These impurities can be deposited on the porous graphite by various established metallizing techniques or their salts can simply be added to the denuding steam or water to be carried to the amalgam/porous graphite interface where they catalyze the decomposition of the amalgam. With the said catalytic materials present, cathode current densities in excess of 1 amp/sq. cm. or 10,000 amps per square meter can be attained without amalgam decomposition within the electrolysis compartment (compartment I).

In the stationary film mercury cell working at commercial cathode current densities the decomposition of amalgam occurs rapidly without much sodium buildup in the mercury. This especially true when metallic impurities are present at the amalgam/porous graphite interface. Less than 0.02 sodium was found in the amalgam at cathode current densities of up to 1 amp/sq. cm. In conventional mercury cells the concentration of sodium in the amalgam ranges from 0.01% in the inlet to 0.35% at the outlet. This increase in sodium concentration results in a 150 mv. increase in cathode reversible EME, going from 1.68 volts at 0.01% sodium to 1.83 volts for the 0.35% sodium concentration, all at 80° C. in 250 gm./l. sodium chloride. With the present stationary film mercury cell having a sodium concentration in the amalgam approximately that of the inlet end of a conventional mercury cell a voltage saving of around 90 mv. is gained over a conventional mercury cell having an average of 0.17% sodium in the mercury.

A further benefit of having a low sodium concentration in the mercury is that the level of metallic impurities that can be tolerated in the feed brine can be increased without an excessive amount of hydrogen being generated. On the other hand, if the impurities are kept at the low level used in current mercury cell practice, then, because of the low sodium level in the amalgam, the amount of hydrogen generated in the cell is lowered. This is beneficial both from a safety point of view and by increasing the sodium hydroxide current efficiency.

A considerable loss in current efficiency in conventional mercury cells is attributed to the following reactions:

These reactions combined results in approximately a 5% loss in current efficiency. Using the stationary film mercury cell of this invention, the rates of these reactions are considerably reduced because of the low sodium concentration in the amalgam. This results in further increased operating efficiency for the cell.

The production of strong sodium hydroxide solution (10-50% by weight) in a single pass through the porous graphite necessitates the use of relatively small quantities of denuding water. It is important, therefore, that almost all the water added migrate to the porous graphite/amalgam interface, to continue an efficient denuding of the amalgam. A preferred method of doing this is to feed steam, rather than water, into and through the porous graphite. The large volume of steam produced from a given volume of water ensures an even distribution of water vapor in the porous graphite, thus preventing areas of undenuded amalgam which can occur if water is used, and there is some preferential channeling of water through the porous graphite. Also, as previously indicated, the cell temperature will generally be kept below 100° C. As a result there is a tendency for much of the steam to condense out at the amalgam/porous graphite interface which

is precisely where the water is needed for efficient denuding.

To provide for the desired denuding action and also fairly even steam (and/or water) distribution into and through the porous graphite, it is desirable that the porous plate be not too thick and also that its porosity characteristics be closely controlled. Toward these ends, a fine carbon aggregate mix having a maximum grain size of 0.01 inch will typically be employed in making the porous graphite body, and the thickness of graphite body used will typically be between about 0.25 and about 0.05 inch, with a thickness of about 0.1 inch preferred.

As a guide to the characteristics of the porous graphite support member employed in the present invention and for purposes of comparison, the following table is set forth, showing typical properties of "porous," "normal" and "high density" graphite.

50

The porous graphite member employed in the present invention will preferably possess an apparent density between about 0.8 and about 1.2 grams per cubic centimeter, an average pore diameter between about 30 and about 150 microns, typically 50 microns, a permeability in darcys in the X, Y and Z directions of at least about 10 darcys, and a total accessible porosity of at least about 30%.

The porous, non-amalgamable member must be electrically conductive so that the lower compartment can act as a short-circuited battery with the amalgam acting as anode, the porous member acting as cathode for hydrogen discharge, and the lower compartment reaction products acting as electrolyte, with some sites on the porous member forming the short-circuit from the cathode to the amalgam anode. Porous graphite having an electrical resistivity typically between about 80 and about 150×10⁻⁵ ohm-inches is preferred for this purpose.

Electrolyte solutions of alkali metal salts other than of sodium chloride may be employed in the present invention, particularly brines of alkali metal halides, for example, of potassium chloride and lithium chloride, and solutions of other alkali metal salts such as of sodium sulfate. Electrolyte solutions of suitable alkaline earth metal salts, such as the chlorides of calcium, strontium and of barium, may also be employed.

75

Decomposing fluids or oxidants other than water or steam (or together with water or steam) also can be employed. Aqueous and non-aqueous solutions of oxidants can be employed. For example, water or steam and carbon dioxide in combination may be employed as the oxidant, in which case a reaction product would be an alkali or alkaline earth metal carbonate; methyl alcohol may be used as the oxidant in the electrolysis of a sodium salt in which case a reaction product would be sodium methylate; or an aqueous polysulfide solution may be employed as the oxidant in the electrolysis of a sodium salt in which case a reaction product would be sodium sulfide.

In addition to the previously indicated objects, the attainment of which represent many general advantages of the present invention, it should also be noted that the cell of this invention also offers several specific advantages over conventional mercury cells, including the following:

(a) The low average sodium concentration in the amalgam compared to conventional mercury cells lowers the cathode reversible EMF and overvoltage giving rise to a voltage saving;

(b) The impurity level in the feed brine can be increased without increasing hydrogen evolution above its present level;

(c) With a pure feed brine, the amount of hydrogen evolved from the cathode and discharged with the chlorine is reduced, increasing both safety and sodium hydroxide current efficiency; and

(d) The substantial loss in current efficiency in conventional mercury cells, due to chlorine reacting with the amalgam, is reduced, due to the low sodium concentration in the amalgam. This also results in an increase in current efficiency.

The foregoing describes my invention but I intend to be limited only by the scope of the appended claims.

I claim:

1. A method for the electrolysis of an electrolyte solution of an alkali or suitable alkaline earth metal salt wherein said electrolysis is carried out in an electrolytic cell comprising two distinct reaction compartments separated by a stationary, substantially horizontal layer of mercury, said method including the steps of:

(a) Introducing the electrolyte solution into an upper compartment having a mercury cathode layer and at least one anode positioned above said layer to form a suitable electrode gap;

(b) Applying a potential between the anode and the cathode whereby the electrolyte is decomposed to liberate the anode electrolysis products at the anode and the alkali or alkaline earth metal is deposited into the mercury cathode to form the alkali or alkaline earth metal amalgam;

(c) Withdrawing the electrolyte and the anode electrolysis products from said upper compartment;

(d) Introducing an oxidant for said alkali or alkaline earth metal into a lower compartment below the mercury through an electrically conductive, porous, non-amalgamable member which is in direct contact with the bottom of the mercury layer and which supports same, said porous support member being permeable to the oxidant but impermeable to the mercury under the cell operating conditions;

(e) Reacting said oxidant for said alkali or alkaline earth metal with the metal amalgam produced in the upper compartment; and

(f) Removing the reaction products from said lower compartment by applying a vacuum to the underside of said porous, electrically conductive support member.

2. A method according to claim 1 wherein the electrolyte solution is an aqueous solution.

3. A method according to claim 1 wherein the reaction step (e) is carried out in the presence of an amalgam decomposition catalyst.

4. A method according to claim 1 wherein the potential is applied by means of suitable electrical connections made to the anode and to the mercury cathode through the electrically conductive, porous member.

5. A method according to claim 1 wherein the potential applied between the anode and the cathode is between the decomposition potential of the alkali or alkaline earth metal salt and about 6 volts.

6. A method according to claim 1 wherein the vacuum applied to the underside of the porous, electrically conductive support member is between about 500 and 730 mm. of mercury.

7. A method according to claim 1 wherein the electrolyte solution employed is of a sodium salt, wherein the oxidant is methyl alcohol, and wherein the reaction products removed in step (f) include sodium methylate.

8. A method according to claim 1 wherein the electrolyte solution employed is of a sodium salt, wherein the oxidant is an aqueous polysulfide solution and wherein the reaction products removed in step (f) include sodium sulfide.

9. A method according to claim 1 wherein the said porous member is porous graphite.

10. A method for the electrolysis of an aqueous electrolyte solution of an alkali or suitable alkaline earth metal salt wherein said electrolysis is carried out in an electrolytic cell comprising two distinct reaction compartments separated by a stationary, substantially horizontal layer of mercury, said method including the steps of:

(a) Introducing the aqueous electrolyte solution into an upper compartment having a mercury cathode layer and at least one anode positioned above said layer to form a suitable electrode gap;

(b) Applying a potential between the anode and the cathode whereby the electrolyte is decomposed to liberate the anode electrolysis products at the anode and the alkali or alkaline earth metal is deposited into the mercury cathode to form the alkali or alkaline earth metal amalgam;

(c) Withdrawing the electrolyte and the anode electrolysis products from said upper compartment;

(d) Introducing an oxidant for said alkali or alkaline earth metal comprising water or steam into a lower compartment below the mercury through an electrically conductive, porous, non-amalgamable member which is in direct contact with the bottom of the mercury layer and which supports same, said porous support member being permeable to the oxidant but impermeable to the mercury under the cell operating conditions;

(e) Reacting said oxidant for said alkali or alkaline earth metal with the metal amalgam produced in the upper compartment; and

(f) Removing the generated reaction products from said lower compartment by applying a vacuum to the underside of said porous, electrically conductive support member.

11. A method according to claim 10 wherein the oxidant introduced in step (d) is water or steam alone and wherein the reaction products removed in step (f) are hydrogen and an alkali or alkaline earth metal hydroxide.

12. A method according to claim 10 wherein the oxidant introduced in step (d) includes some carbon dioxide and wherein the reaction products removed in step (f) include an alkali or alkaline earth metal carbonate.

13. A method for electrolysis of sodium chloride brine wherein said electrolysis is carried out in an electrolytic cell comprising two distinct reaction compartments separated by a stationary, substantially horizontal layer of mercury, said method including the steps of:

(a) Introducing the brine into an upper compartment having a mercury cathode layer and at least one anode positioned above said layer to form a suitable electrode gap;

- (b) Applying a potential between the anode and the cathode whereby the brine is decomposed to liberate chlorine at the anode and sodium is deposited into the mercury cathode to form sodium amalgam;
- (c) Withdrawing sodium chloride brine and chlorine from said upper compartment;
- (d) Introducing water or steam into a lower compartment below the mercury through an electrically conductive, porous, non-amalgamable member which is in direct contact with the bottom of the mercury layer and which supports same, said porous support member being permeable to water and steam but impermeable to the mercury under the cell operating conditions;
- (e) Reacting said water or steam with the sodium amalgam produced in the upper compartment; and
- (f) Removing the generated hydrogen and sodium hydroxide solution from said lower compartment by applying a vacuum to the underside of said porous, electrically conductive support member.

14. An electrolytic cell for the electrolysis of an electrolyte solution of an alkali or suitable alkaline earth metal salt comprising two distinct reaction compartments separated by a stationary, substantially horizontal layer of mercury, said reaction compartments comprising:

- (a) an upper compartment for containing the electrolyte solution, said upper compartment having a mercury cathode layer, at least one anode positioned above said layer to form a suitable electrode gap, means for introducing the electrolyte and means for withdrawing the electrolyte and anode electrolysis products; and
- (b) a lower compartment below the mercury having an electrically conductive, porous, non-amalgamable member which is in direct contact with the bottom of the mercury layer and which supports same, means for introducing an oxidant for said alkali or alkaline earth metal into and through said porous member, and means for removing reaction products resulting from the reaction between the oxidant and the metal amalgam produced in the upper compartment, said porous member being permeable to the metal oxidant but impermeable to the mercury;

said cell also having means for applying a potential between the anode and the cathode, and means for applying a vacuum to the underside of said porous, electrically conductive support member.

15. An electrolytic cell according to claim 14 wherein the said porous member is porous graphite.

16. An electrolytic cell according to claim 14 wherein said porous support member is structurally supported on its underside by a perforated metal base.

17. An electrolytic cell according to claim 16 wherein the upper face of the metal base is attached to the underside of the porous support member by means of an electrically conductive cement.

18. An electrolytic cell for the electrolysis of an aqueous electrolyte solution of an alkali or suitable alkaline earth metal salt comprising two distinct reaction compartments separated by a stationary, substantially horizontal layer of mercury, said reaction compartments comprising:

- (a) an upper compartment for containing the electrolyte solution, said upper compartment having a mercury cathode layer, at least one anode positioned above said layer to form a suitable electrode gap, means for introducing the electrolyte and means for withdrawing the electrolyte and anode electrolysis products; means in said compartment for applying an externally applied electrical potential between the anode and the cathode whereby the electrolyte is decomposed to liberate the anode electrolysis products and the alkali or alkaline earth metal is deposited into the mercury cathode to form the corresponding amalgam; and

- (b) a lower compartment below the mercury wherein an oxidant for said alkali or alkaline earth metal is introduced into and through an electrically conductive, porous, non-amalgamable member which is in direct contact with the bottom of the mercury layer and supports same, said porous support member being permeable to the oxidant but impermeable to the mercury under the cell operating conditions, wherein said oxidant reacts with the metal amalgam produced in the upper compartment, and wherein said reaction products are drawn off from said lower compartment by means of a vacuum applied to the underside of said porous, electrically conductive support member.

19. An electrolytic cell for the electrolysis of an aqueous electrolyte solution of an alkali or suitable alkaline earth metal salt comprising two distinct reaction compartments separated by a stationary, substantially horizontal layer of mercury, said reaction compartments comprising:

- (a) an upper compartment for containing the electrolyte solution, said upper compartment having a mercury cathode layer, at least one anode positioned above said layer to form a suitable electrode gap, means for introducing the electrolyte and means for withdrawing the electrolyte and anode electrolysis products; means in said compartment for applying an externally applied electrical potential between the anode and the cathode whereby the electrolyte is decomposed to liberate the anode electrolysis products and the alkali or alkaline earth metal is deposited into the mercury cathode to form the corresponding amalgam; and

- (b) a lower compartment below the mercury wherein an oxidant for said alkali or alkaline earth metal comprising water or steam is introduced into and through an electrically conductive, porous, non-amalgamable member which is in direct contact with the bottom of the mercury layer and supports same, said porous support member being permeable to the oxidant but impermeable to the mercury under the cell operating conditions, wherein said oxidant reacts with the metal amalgam produced in the upper compartment, and wherein the generated reaction products are drawn off from said lower compartment by means of a vacuum applied to the underside of said porous, electrically conductive support member.

20. An electrolytic cell for the electrolysis of sodium chloride brine comprising two distinct reaction compartments separated by a stationary, substantially horizontal layer of mercury, said reaction compartments comprising:

- (a) an upper compartment for containing the brine, said upper compartment having a mercury cathode layer, at least one anode positioned above said layer to form a suitable electrode gap, means for introducing the brine, and means for withdrawing brine and chlorine; means in said compartment for applying an externally applied electrical potential between the anode and the cathode whereby the brine is decomposed to liberate chlorine at the anode and sodium is deposited into the mercury cathode to form sodium amalgam; and

- (b) a lower compartment below the mercury wherein water or steam is introduced into and through an electrically conductive, porous, non-amalgamable member which is in direct contact with the bottom of the mercury layer and supports same, said porous support member being permeable to water and steam but impermeable to the mercury under the cell operating conditions, wherein said water or steam react with the sodium amalgam produced in the upper compartment, and wherein the hydrogen and sodium hydroxide solution generated are drawn off from said lower compartment by means of a vacuum

11

applied to the underside of said porous, electrically conductive support member.
